UNITED STATES PATENT OFFICE

MELVILLE KEIM, OF CHICAGO, ILLINOIS, ASSIGNOR TO APEX PRODUCTS CORP., OF CHICAGO, ILLINOIS, A CORPORATION OF ILLINOIS

DESIGN FOR A VAPORIZER

Application filed December 9, 1929. Serial No. 33,715. Term of patent 14 years.

To all whom it may concern:

Be it known that I, MELVILLE KEIM, a citizen of the United States, residing at Chicago, in the county of Cook and State of Illinois, have invented a new, original, and ornamental Design for a Vaporizer, of which the following is a specification, reference being had, to the accompanying drawing forming a part thereof.

Referring to the drawing:

The single figure is a perspective view of a vaporizer embodying the design of my invention.

My present invention relates to a container for an evaporable substance capable of giving out vapors for the purpose of deodoriz-

ing the atmosphere, exterminating insects, or any similar purpose. The container is adapted to form a package in which the evaporable substance may be marketed, the package being conditioned for use by removing a film of celophane, which seals but does not hide the openings in the curved front face of the container.

The container also is, or may be, provided with a loop by which the same may be hung in any convenient place, as from a coat hook in a closet.

I claim:

The ornamental design for a vaporizer as shown and described.

MELVILLE KEIM.
